UNITED STATES PATENT OFFICE

2,484,877

SHOE UPPER MOLDING MACHINE

Milton L. Dodge, Newburyport, Mass.

Application December 4, 1946, Serial No. 713,981

6 Claims. (Cl. 12—97)

1

This invention relates to the molding of shoe uppers, particularly the vamp, preliminary to lasting, and while not restricted thereto is of particular value in the preparation of a shoe upper for slip lasting, since it provides for crimping the vamp longitudinally to its back edge in all vertical and horizontal planes to last shape and curves in the lower margin around the side and toe, without requiring longitudinal seams in the upper, to the contour of the sock lining or innersole to which it is secured preparatory to slip lasting.

It may, however, turn in the margins, which facilitates lasting by other methods than slip lasting.

A further object is to shape a moldable toe stiffener together with the upper in a single operation, whether or not the upper is seamed.

Still another object is to provide a machine wherein the shoe upper on a last-shaped form is presented to a stretchable sheet of material which is stretched around the form, pressing and wiping the vamp to the contour of the form, the machine being an improvement over that shown in my application for patent Serial No. 871,232, filed May 21, 1946, for Machine for shaping shoe end portions.

For a complete understanding of this invention, reference may be had to the accompanying drawings in which

Figures 1 and 2 are front and side elevations, respectively, of a vamp molding machine embodying the invention.

Figure 1a is a fragmentary top plan view of the wipers and related parts.

Figure 3 is a plan view of a vamp preparatory to the molding operation.

Figure 4 is a sectional view on line 4—4 of Figure 3.

Figures 5 and 6 are fragmentary central vertical sectional views through the molding elements and vamp showing successive stages in the operation of the machine.

Figure 7 is a sectional view on line 7—7 of Figure 6.

Figure 8 is a view similar to a portion of Figure 7, but showing a modification particularly suitable in connection with slip lasting.

Figure 9 is a view similar to Figure 4, but showing the vamp fully molded and in condition for attachment to a sock lining or innersole preparatory to slip lasting.

Figure 10 is a sectional view on line 10—10 of Figure 9.

Figures 11, 12 and 13 are perspective views of

2

slippers having the vamp variously constructed and molded to the desired contours.

Referring first to Figures 1 and 2, the molding machine comprises a standard 1 which is adapted to be secured to the forward face of a table 2 as by bolts 3, the standard itself projecting rearwardly of the forward edge of the table through a slot therein. This standard 1 is provided with an upstanding arm 4 carrying at its forward end a support 5. Slidably mounted on this support are a pair of side wipers 6 (see Figures 1, 2, 5 and 6). These wipers 6 are supported at the forward end of an axially movable bar 8 which is slidable through the upstanding arm 4, and at its rear end is engaged by the upper portion of a cam element 9 pivoted at 10 at its lower end to a bracket 11 extending rearwardly from the standard 1.

The wipers 6, as shown best in Figure 2, are engaged on their outer faces by actuating rollers 20 15 journaled between forks 16 which are adjustable laterally by screws 17 threaded through horizontal arms 18 pivoted at 19 to the bracket 5. Engaging the outer edges of the arms 18 are extensions 20a of arms 20 pivoted at 21 between the 25 sides of a forked extension 22 at the forward edge of the standard 1. Their lower ends have pivoted thereto a pair of links 23 which are pivoted together at 24 and engaged on the pivot is a vertical stem 25 mounted for vertical motion through 30 a guide boss 26 projecting forwardly from the standard 1 beneath the level of the table. This stem 25 is provided with a longitudinal slot 25a through which extends a pin 27 carried by a pair of links 28, which at their lower ends are pivoted on a cross pin 29 to a hand lever 30 fulcrumed at 31 to the lower end portion of the standard 1. The rear end of the hand lever 30 is pivoted at 32 to the lower end of a sleeve 33 which is telescopically related to a rod 34 secured at its 35 upper end to a member 35. The upper end of the member 35 is pivoted to a lever 36 fulcrumed at 37 at the top of the standard 4 and above the table 5. This lever 36 carries at its forward end a downwardly extending arm 38 to the lower end 40 of which is fixed a molding form 39. This molding form is shaped to general last contour and is arranged with its sole face 40 upwardly faced. The sleeve 33 and the member 35 are connected together by a pair of toggle links 45 provided at their pivotal connection to each other with a roll 46 which may engage with a cam bar 47 angularly and vertically adjustable on a bracket extension 48 of the table 2.

As the forward end of the handle 30 is depressed, the sleeve 33 is lifted and pressure is

55

imparted through the nearly aligned toggle links 45 to the member 35, lifting the rear end of the lever 36 and depressing the form 39, the roll 46 bearing against the cam 47. This form is depressed between the wipers 6 against a sheet of stretchable material 50, such as rubber, the upper margins of which overlie the wipers 6 and are suitably secured thereto. This sheet material 50 is of such a size that when the form 39 is pressed downwardly thereinto, it is stretched so that when a flat tempered vamp 55, such as is shown detached in Figures 3 and 4, is placed between the form 39 and the sheet material 50 and the form is then pressed against the sheet, this sheet material presses the vamp against the form and as the pressure continues, wipes the vamp around the form and to its contour. The portions of the sheet material which engage about the sides of the form as the material stretches, move bodily along the form, thus to produce the wiping effect desired. When the form 39 is depressed sufficiently to pass below the wipers, the cam roll 46 rides out on the rounded upper end of the cam bar 47 allowing the toggle to break and discontinuing the downward swing of the former 39, and the wipers are brought inwardly over the sole face of the form, being moved inwardly by the swinging of the arms 20 after the lost motion of the pin 27 within the slots 26 has been taken up, and forwardly by the impingement on the cam 9 of a roll 60 carried by an arm 61 projecting upwardly from the sleeve 33. It will be noted that the form 39 is of sufficient length to provide for shaping the contour of the vamp throughout its full length, even when the vamp is provided with a vamp reinforce at its upper end as shown at 65 on Figure 4.

In order to reduce the wear on the sheet material 50 around the margins of the form, an apron 67 formed of a strip of leather, or like material, may overlie the marginal portion of the sheet material 50 and be clamped at its outer edge by the means which secures the marginal portion of the sheet material. This apron engages the vamp where the greatest slip on the vamp occurs during the molding operation.

The form 39 may be angularly adjustable, if desired, as shown in Figure 2, the arm 38 being fixed to a T-block 68 pivoted at 38a to the lever 36, adjusting screws 69 threaded through the head of the T bearing against the lever 36 on either side of the pivot 38a.

The cam member 9 is held up against an adjustable abutment at the rear end of the bar 8 as by a spring 9a, and the rearward thrust on the wipers 6, caused by the pressure exerted by the form 39 when it is lowered and before the wipers are moved forwardly, is cushioned by a spring 8a as shown in Figure 2.

When the vamp is employed for a shoe which is to be lasted after it has been assembled on a last, the lower margin of the vamp is so cut as to extend above the sole face of the form as shown in Figures 5 and 6 at 66. When the side and end wipers are moved inwardly, this margin is therefore wiped and turned in over the sole face of the form toward a common plane as shown in Figure 6. These turned-in portions are not secured in place, however, so that it is an easy matter, when the form with the vamp molded therearound is removed from between the wipers, to remove the vamp from the form, but the folding inwardly of the margins of the vamp so shapes these margins that it is an easy matter

during the lasting operation to bring them in over the last and secure them in any desired manner without the necessity of any substantial pulling operations.

In case the vamp is to be used in a slip lasted shoe, it will be cut shorter than where it is pulled over the last, and commonly, also, the sole face of the form will be extended upwardly so that the edge of the vamp will terminate below it as shown in Figure 8, so that when the vamp is removed it will be contoured as shown in Figures 9 and 10 with its lower edges turned downwardly in condition for the margin of a sock lining or innersole (not shown) to be stitched thereto preparatory to slip lasting.

It will also be noted that the forming operation is extended backwardly to the full extent of the vamp and that where a vamp reinforce 65 is employed, this also is shaped to the desired contour. It will also be noted that this molding is done without requiring any cutting of the vamp as has heretofore been commonly done, particularly in the case of slip lasted shoes, in order to shape the vamp to a contour which will facilitate the slip lasting operation. For example, it has been common practice to notch the forward end portion of the vamp, bringing the portions at each side of the notch together and stitching them together over the toe portion as shown at 70 in Figure 11.

Sometimes, also, the vamp has been made in two pieces joined together centrally as by the seam 71, as shown in Figure 13, the mating edges 35 at the seam 71 being so cut along curves as to provide the desired contour of the vamp. Sometimes, also, the vamp has been made with a lower upstanding strip 72 to the upper edge of which is stitched a top piece 73 as is shown in Figure 12, to form a shoe having the appearance of the moccasin type.

With the forming operation of this machine it is quite unnecessary to resort to any of the constructions shown in Figures 11, 12 and 13. However, if shoes of this type are desired, they may be so formed and the molding operation will then serve to improve their contours and make the slip lasting operation substantially easier. Also, in any case where desired, a moldable toe stiffener 50 may be associated with the vamp and molded together therewith, such a stiffener being shown, for example, at 75 in Figures 3, 4, and 9.

It will be noted that the method carried out by this machine molds the vamp to the desired contour in all vertical and horizontal planes throughout its full length in a single operation.

From the foregoing description of an embodiment of this invention, it will be understood that various changes and modifications may be made therein without departing from the spirit or scope of the invention.

I claim:

1. In combination, a support, wipers carried by said support for motion toward and from each other, a sheet of stretchable material supported about its margin by said wipers, a form having substantially the contour of the toe portion of a last, means supporting said form for motion toward and from said sheet material to pass between said wipers against said sheet material and cause said sheet material to be wrapped about and stretched over the top face and toe end of said form and to conform a vamp between said form and sheet material to the surface of said form, and means for thereafter moving said wipers in over the sole face of said form.

2. In combination, a support, wipers movable on said support toward and from each other, a sheet of stretchable material depending between said wipers and supported about its margin, a toe form, an arm pivoted above said support and supporting said form to swing downwardly and toward said wipers and in stretching relation to said sheet material therebetween, and means actuatable to move said wipers inwardly over the sole face of said form.

3. In combination with a support, a standard fixed to said support and extending thereabove, wipers movable across the upper face of said support, a sheet of stretchable material bridging said wipers and depending therebetween, an arm pivoted on said standard, an element shaped to the contour of the forepart of a last, a lever pivoted to said standard above said support and carrying said element for motion between said wipers against and in stretching relation to said sheet material, a pair of arms pivoted to said standard and operatively connected to said wipers for moving said wipers laterally, a member connected to said wipers for forward and rearward motion, and actuating mechanism operatively connected to said lever, to said arms, and to said member movable to press said element between said wipers and against said sheet material with a shoe vamp therebetween, and thereafter to move said wipers in over the sole face of said element.

4. In combination with a support, a standard fixed to said support and extending thereabove, wipers movable across the upper face of said support, a sheet of stretchable material bridging said wipers and depending therebetween, an arm pivoted on said standard, an element shaped to the contour of the forepart of a last, a lever pivoted to said standard above said support and carrying said element for motion between said wipers against and in stretching relation to said sheet material, a pair of arms pivoted to said standard and operatively connected to said wipers for moving said wipers laterally, a member connected to said wipers for forward and rearward motion, an actuating lever, a cam follower connected for movement with said lever, a cam on said member for cooperation with said follower to move said member and wipers forwardly on sufficient motion of said actuating lever from starting position, a connection from said actuating lever to said element-carrying lever for moving said element into and out of position between said wipers and into and out of stretching relation to said sheet material, and a lost motion connection between said actuating lever and arms whereby on rocking said actuating lever in one direction said element is moved between said

wipers and into stretching relation to said sheet material and thereafter said wipers are moved in over the sole face of said element.

5. In combination with a support, a standard fixed to said support, wipers movable across the upper face of said support, a last shaped form, means supporting said form for motion transverse to and between said wipers, means cooperating with said form when said form is at one end of its stroke pressing a vamp against said form, means actuatable to move said wipers inwardly over said form and actuatable to move said form, operative connections from said actuatable means to said wipers including a lost motion mechanism, and operative connections between said actuatable means and said form including mechanism releasable after a predetermined extent of motion of said form whereby said form is first moved to said end of its stroke and then said wipers are moved inwardly when said actuatable means is actuated in one direction.

6. In combination with a support, a standard fixed to said support, wipers movable across the upper face of said support, a last shaped form, means supporting said form for motion transverse to and between said wipers, means cooperating with said form when said form is at one end of its stroke pressing a vamp against said form, means actuatable to move said wipers inwardly over said form and actuatable to move said form, operative connections from said actuatable means to said wipers including a lost motion mechanism, and operative connections between said actuatable means and said form including mechanism releasable after a predetermined extent of motion of said form whereby said form is first moved to said end of its stroke and then said wipers are moved inwardly when said actuatable means is actuated in one direction, said releasable means including a toggle and a cam along which said toggle moves shaped to permit breaking of said toggle to release said form from said actuatable means after said actuatable means has been moved to a predetermined extent from a starting position.
